(57) **CLAIM**

The ornamental design for a windscreen wiper spoiler, as shown and described.

DESCRIPTION

FIG. 1 is a perspective view of a windscreen wiper spoiler showing the claimed design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an enlarged top view of FIG. 6; and,

FIG. 9 is an enlarged bottom view of FIG. 7.

The broken lines in FIGS. 6-9 illustrate the periphery of the enlarged views of the windscreen wiper spoiler and form no part of the claimed design.
